COMPENSATING APPARATUS FOR CONTOUR TURNING

Delbert I. Wilson, Dayton, Ohio, assignor to The City Engineering Company, Dayton, Ohio, a corporation of Ohio

Application July 20, 1942, Serial No. 451,567

9 Claims. (Cl. 82—28)

This invention relates to screw machines wherein the stock is fed by means of a cam operated mechanism, and particularly the invention relates to a mechanism for compensating the error of movement of a device actuated by a cam when the motion is transmitted through a lever system. In machines of various types it is conventional to actuate different mechanisms by means of a cam whose surface is engaged by one end of a lever so that rotation of the cam produces movement of a device adapted to be actuated by the lever. Such mechanisms have particular use on screw machines wherein cams are mounted upon a cam shaft and are adapted to be engaged by one end of a lever, the opposite end of the lever engaging a mechanism to move the turning tools, or to move the spindle of the machine for feeding the stock adjacent the tools. When the lever is rotated upon its pivot, the end thereof that engages the surface of the cam swings in an arc about the pivot for the lever and thereby introduces an error into the movement of the lever which can only be cured by providing a specially ground surface on the face of the cam. The cam cannot be precalculated and ground to the shape determined mathematically but rather the cam must be first produced mathematically and then reground by a trial and error process to correct the error produced by the arcuate movement of the lever that engages the cam surface.

An object of the invention is to provide an arrangement of a cam and lever system that avoids all error in the movement of the lever due to the arcuate travel of the end of the lever for transmitting the motion of the cam to a driven device.

Another object of the invention is to provide a cam and lever system for producing motion of a device wherein the means engaging the cam in the lever system moves in a straight line even though the end of the lever that picks up the motion of the cam moves in an arc, whereby error produced by the arcuate movement of the end of the lever is eliminated.

Another object of the invention is to provide a lever system adapted to cooperate with the cam for transmitting motion to a device wherein the ends of the lever system have a predetermined movement ratio, and wherein the member that engages the cam moves in a straight line to prevent the introduction of any error in the ratio of movement between opposite ends of the lever system.

Another object of the invention is to provide a screw machine with a cam and lever system for feeding the stock through the screw machine

wherein the lever system is provided with a compensating device for engaging the cam that produces the feeding movement of the stock to eliminate errors in the feeding of the stock due to arcuate movements of the levers in the lever system.

Another object of the invention is to provide a machine wherein longitudinal movement of a device is controlled by means of a cam that produces motion in a lever system for moving the device, and wherein means is provided between the cam and the lever system for compensating error developed by the lever system due to the arcuate movement of the end of the lever that receives its motion from the surface of the cam.

Another object of the invention is to provide an apparatus wherein a portion of the apparatus is controlled in longitudinal movement by means of a cam which transmits motion through a lever system, and wherein a cam follower is disposed between the cam and the lever system to prevent error in the movement of the longitudinally driven portion as caused by the arcuate movement of a lever in engagement with the surface of the cam.

Another object of the invention is to provide an apparatus wherein longitudinal movement of a portion of the apparatus is produced by means of a lever system as actuated by means of a cam and a cam follower is disposed between the cam and the lever system in a manner that the follower moves in a straight line to eliminate errors that would normally be transmitted through the lever system if the end thereof engages the cam and follows its normal arcuate path while in engagement with the cam.

Another object of the invention is to provide a machine wherein longitudinal motion is produced in a portion of the machine by means of a lever system that receives its motion from a cam, and wherein the lever system is constructed and arranged in a manner that a cam having a precalculated contour can be placed on the machine and the lever system will accurately transfer the dimensions calculated to be produced by the cam upon a workpiece.

Another object of the invention is to provide a machine having a cam and lever system constructed and arranged in accordance with the foregoing object wherein the contour of the cam can be precalculated to cooperate perfectly with the contour of a second cam to produce tapers or other special forms upon a workpiece.

Another object of the invention is to provide a screw machine wherein the spindle is adapted

to be moved longitudinally for feeding stock that is operated by a cam and lever system and arranged in accordance with any of the foregoing objects.

Further objects and advantages will become apparent from the drawings and the following description.

In the drawings:

Fig. 1 is a side elevational view, partly in cross-section, of a screw machine incorporating features of this invention.

Fig. 2 is an elevational view of a portion of the screw machine of Fig. 1 showing the mechanism for longitudinally moving the spindle of a screw machine for feeding stock past the turning tools.

Fig. 3 is an end elevational view of the screw machine taken along line 3—3 of Fig. 1 showing the cam and lever system of this invention.

Fig. 4 is an elevational view, partly in cross-section, showing the turning tools and the cam means for operating the same.

Fig. 5 is a cross-sectional view taken along line 5—5 of Fig. 3.

Fig. 6 is a horizontal cross-sectional view taken along line 6—6 of Fig. 3.

Fig. 7 is a vertical cross-sectional view taken along line 7—7 of Fig. 6.

Fig. 8 is an elevational view of a workpiece that can be produced by the apparatus of this invention.

In machine tools of various kind, some of the mechanisms are actuated by means of a pivoted lever that is engaged on one end by a cam to produce motion in the opposite end of the lever and thereby operate a mechanism of the machine. The cam, of course, rotates upon a fixed center or upon a cam shaft. A fixed point on the lever is adapted to engage the surface of the cam and since the lever is pivoted the fixed point on the lever will travel in an arc about the pivot center of the lever. This arcuate movement of the cam follower or fixed point on the lever causes the point of contact of the cam follower with the cam to change toward the pivot center of the lever as the lever rotates about its pivot center. If a cam is produced having a precalculated contour for producing a predetermined movement of a mechanism of the machine, this change in the contact point of the cam follower upon the cam surface produces a variation in the movement transmitted to the lever that is not desirable, since it is necessary to rework the cam to eliminate the error, and this can only be done by a trial and error process and the production of products on the machine to determine the actual effect of the cam upon the operation of the machine. Such errors are particularly noticeable when it is desired to produce an article having a tapered surface or some other special contour, it being necessary to rework the cam from its precalculated contour by a careful grinding of the surface until the desired effect is produced upon the lever actuated by the cam to produce the desired taper or special contour.

All of this trial and error in the manufacture of cams, and the error in the lever system operated by the cam, can be overcome if the point of contact of the cam follower upon the cam is always in the same radial position upon the cam, that is the point of contact of the cam follower must move in a straight line radially from the center of rotation of the cam.

There are many movements of levers produced by cams that can have their operation improved

by the apparatus of this invention. However, for the purpose of illustration the invention herein is applied for use upon a screw machine, and particularly for producing the feeding operation of the work stock through the screw machine, and more particularly the movement of the spindle of a screw machine that feeds the work stock past the turning tools. When the apparatus of this invention is used in the manner disclosed herein, the longitudinally turned dimensions upon a piece of stock is very accurately maintained and the cam for producing the dimensions can be mathematically calculated for its contour without any possibility of error being transmitted through the lever system.

In this invention the apparatus is applied upon a screw machine 10 having a base 11 that supports a main machine frame 12. The machine frame 12 supports a spindle 13 that is provided with a dovetail guide 14 adapted to slide in a dovetail guideway 15 provided in the frame 12. The spindle 13 is adapted to receive the work stock 16 and to frictionally engage the same so that movement of the spindle 13 longitudinally in the guideway 15 will feed the work stock 16 through a work stock guide bushing 17 carried in the guide bushing support 18.

The base 11 supports an electric motor 19 that is directly connected to a speed change device 20 for controlling the speed of the drive shaft 21. A suitable hand control member 22 is provided for regulating the operation of the speed changer 20. A flat pulley 23 is keyed to the drive shaft 21 and drives a belt 24 that engages the spindle 13 for driving the same and thus for rotating the work stock 16.

The turning tools 25 and 26, see Fig. 4, are supported in tool holders 27 and 28, respectively, that are carried upon a rocker arm 29 pivoted upon the pin 30 that extends from the guide bushing support 18. The tool holder 28 is provided with a micrometer adjustment 31 for regulating the position of the cutting edge of the tool 26 transversely with respect to the work stock 16. A similar micrometer adjustment is provided for longitudinally adjusting the tool support 28 to move the turning tool 26 longitudinally with respect to the work stock 16 and thereby adjust its position with regard to the turning tool 25. Similar micrometer adjustments may also be provided for the tool holder 27, thereby regulating the transverse and longitudinal positions of the turning tools 25 and 26 with regard to each other and with regard to the work stock 16. While there has been shown only two turning tools in this invention it is to be understood that the disclosure is merely representative of a screw machine and that other turning tools can be provided that work from different angles radially from the workpiece for producing various turning operations upon the work stock 16 and can be operated from cams carried upon a cam shaft hereinafter described.

The turning tools 25 and 26 engage the work stock 16 by a transverse movement as produced by a rocking motion of the rocker arm 29 about the pivot 30 caused by a cam 32 secured to a cam shaft 33 and engaged by a cam follower 34 that is secured to the rocker arm 29. The contour of the cam 32 controls the various depth cuts to be made upon the work stock 16 and determines which turning tool 25 or 26 will engage the work stock to produce the various turning operations.

The cam shaft 33 is suitably bearinged upon the frame 12, one of such bearings being shown

at 35. The cam shaft 33 also carries a worm wheel 36 driven by a worm 37 carried upon a shaft 38 that supports a pulley 39 driven by a belt 40 extending from a driving pulley 41 carried upon the shaft 42 of a speed change device 43 driven by an electric motor 44. The speed change device 43 is regulated by means of the manually operated control handle 45 for thus controlling the speed of rotation of the cam shaft 33 and thus controlling the operation of the cam 32 for regulating the speed of transverse movement of the turning tools 25 and 26 with respect to the work stock 16.

The longitudinal movement of the spindle 13 is controlled by means of a cam 50 carried upon the cam shaft 33. The cam 50 is engaged by a cam follower 51, see Fig. 3, carried by a lever 52 that engages a bell crank lever 53 for longitudinally moving the spindle 13.

The lever 52 is pivoted upon a pin 54 that is carried upon a support bracket 55 secured to the machine frame 12 by means of the bolts or screws 56. One end of the lever 52 carries a roller 57 that engages a roller 58 carried upon one end of the bell crank lever 53 that is pivoted to the machine frame 12 by means of a pin 59 carried in a bracket 60.

The opposite end of the lever 52 carries a shoe 61 that is bearinged in the lever 52 by means of the shank 62 provided on the shoe 61. The shank 62 can freely rotate within the bearing bore provided in the lever 52 and thereby permit rotation of the shoe 61. The shoe 61 is disposed in a guideway 63 provided in a slide 64 whereby the shoe 61 can move transversely in the slide 64.

The slide 64 is provided with guideways 65 and 66 that receive guide tracks 67 and 68, respectively, the guide tracks 67 and 68 being secured to the machine frame 12 by means of the bolts or screws 69 and 70, respectively. The cam follower 51 is secured to the slide 64 by means of the bolt or screw 71. The cam follower 51 is provided with a hardened wear plate 72 that engages the surface of the cam 50.

The guide tracks 67 and 68 control the movement of the slide 64 and thus the movement of the cam follower 51 in a straight line. The line of movement of the cam follower 51 is in a straight line radially from the center of rotation of the cam 50 so that regardless of the degree of movement of the cam follower 51 the point of contact of the follower with the surface of the cam 50 will always be in the same relative position radially from the center of rotation of the cam 50. Therefore, when a surface is generated upon the cam 50 having a predetermined rise for a particular number of degrees of rotation of the cam, the movement of the cam follower can be accurately predicted or precalculated. Movement of the slide 64 radially from the center of rotation of the cam 50 causes movement of the shoe 61 radially from the center of rotation of the cam 50 so that the end of the lever 52 engaged by the shoe 61 will be moved accordingly. However, since the shank 62 of the shoe 61 is rotatably carried in the lever 52, the shoe can rotate with respect to the end of the lever 52, and since the end of the lever 52 moves in an arc about the pivot center 54, the shoe will move transversely within the slide 64. This movement of the shoe is in a straight line transversely of the slide 64 and therefore the degree of motion given the lever 52 by the slide 64 through the shoe 61 will always be the same regardless of the arcuate swing of the shank 62.

of the shoe 61. Since all of the motion transmitting movements between the cam 50 and the lever 52 are straight line movements, there will be no error in the degree of motion transmitted to the lever 52 from the rise in the cam 50.

Since the error of motion transmission to the lever 52 has been avoided the contour of the cam 50 can be precalculated and ground to a predetermined accuracy so that when the cam 50 is placed upon the cam shaft 33 a predetermined and precalculated movement of the lever 52 will be produced for transmission to the bell crank lever 53 and thus to the spindle 13. The arm 73 of the bell crank lever 53 is provided with a slot 74 that receives a slide member 75 carrying an antifriction member 76 such as a ball bearing that engages a wear plate 77 carried upon an arm 78 extending transversely from the spindle 13. A nut 79 secures the ball bearing in position upon the slide 75 while a washer 80 and the nut 81 secures the slide in position within the slot 74 in the arm 73 of the bell crank lever 53. The slide 75 receives a threaded rod 82 in threaded engagement therewith for moving the slide 75 longitudinally within the slot 74 and thereby adjusting the effective length of the bell crank arm 53, since the point of contact of the ball bearing 76 upon the wear plate 77 determines the effective length of the lever arm 73. The threaded rod 82 has a shoulder 83 rotatably disposed within the end of the lever arm 73 and retained therein by means of a nut 84. A knurled head 85 is secured to the end of the rod 82 to provide means for rotating the same when adjusting the position of the slide 75.

Rotation of the lever 52 as caused by the cam 50 and the cam follower 51 will produce rotation of the bell crank lever 53 about the pivot 59 thereby causing the ball bearing 76 to engage the wear plate 77 carried by the spindle 13 to move the spindle longitudinally within the guideway 15 for feeding the work stock 16 past the turning tools 25 and 26. Suitable means such as a spring or a weight can be provided for returning the spindle, and for maintaining the wear plate 77 in engagement with the ball bearing 76 so that the movement of the bell crank lever 53 will be accurately transmitted to the spindle 13.

From the foregoing description it will be apparent that all of the motion transmitted from the cam 50 to the spindle 13 are in effect straight line movements so that any error produced by arcuate movements is avoided. The arrangement thus permits a very accurate control over the length of the longitudinal turning operations as produced by movement of the spindle 13 with respect to the turning tools 25 and 26, the spindle 13, of course, carrying the work stock 16 past the turning tools in its forward travel.

The arrangement of the apparatus is particularly advantageous when turning special contours, such as tapers, radii and others on a completely automatic machine, such as standard automatic screw machines. Accurate control over the transverse movement of the turning tool, as well as accurate control over the feeding of the work stock past the turning tool is required when turning tapers on a workpiece, or other special contours, since it is the relationship of forward movement of the work stock and the transverse movement of the turning tool that controls the shape of the contour. The feeding of the work stock by means of a cam and lever system has been particularly troublesome on automatic screw machines due to the error in the

system heretofore referred to. If a predetermined rise was required to produce a predetermined forward motion of the spindle and thus of the work stock past the turning tools, it was not possible to lay out a cam mathematically and know the result on the final workpiece, because the point of contact of the cam follower upon the cam would change in its radial position with respect to the surface of the cam thereby shortening or lengthening the cut made upon the workpiece according to whether the lever was on one side or the other of a horizontal plane at right angles to the radial plane between the point of contact of the cam follower on the cam and the center of rotation of the cam. The apparatus of this invention provides a straight line movement of the cam follower and therefore a precalculated rise on the cam will produce a precalculated movement of the lever regardless the position of the lever so that the relationship between transverse movement of the turning tool and longitudinal movement of the spindle and work stock can be precalculated to produce a special contour upon the surface of the workpiece.

Such a workpiece is shown in Fig. 8 wherein a tapered portion 86 is being turned upon the work stock 16. The work stock 16 is moving in the direction of the arrow thereon, and therefore it becomes necessary to coordinate the transverse movement of the turning tool 25 with respect to the axial movement of the work stock 16 to produce the taper on the tapered portion 86.

While the apparatus of this invention has been described in an association with a particular type of machine, yet it is to be understood that the mechanism is capable of being used on any other machine wherein it is desired to accurately control the transmission of a rise on a cam to a lever system for transmitting the movement to the movable apparatus on the machine, and while the apparatus disclosed herein shows and describes a preferred form of the invention, that the apparatus is capable of mechanical alteration without departing from the spirit of the invention, and that all such modifications of the apparatus as fall within the scope of the appended claims are intended to be included herein.

Having thus fully described my invention, what I claim as new and desire to secure by Letters Patent, is:

1. In a motion transmitting system, the combination of, a cam, a pivoted lever for receiving motion from said cam and adapted to transmit the motion, means engaged by said cam and movable in a straight line radially from said cam, means carried by said first mentioned means and movable thereon in a straight line normal to the straight line movement of the said first means for connecting the same to said lever for accurately transmitting the motion from a predetermined cam rise to said lever.

2. In a motion transmitting system, the combination of, a cam adapted to be rotated, a lever pivotally mounted adjacent said cam, a cam follower, guide means for said cam follower for directing the motion thereof in a straight line radially from said cam, a recess in said follower disposed normal to the straight line motion of said follower, a slide shoe carried upon said follower in said recess and movable at a right angle to the direction of movement of said cam follower, and means connecting said shoe to said lever, whereby a predetermined rise on said cam is accurately transmitted to said lever.

3. In a machine tool, the combination of, a

mechanism adapted to have motion imparted thereto, a lever system for imparting motion to said mechanism, cam means for producing motion in said lever system, means disposed between 5 said cam and said lever system for continuously engaging said cam in a single plane extending radially from said cam, and means connecting said last mentioned means to said lever system to transfer the straight line motion therein to the arcuate movement of a lever of said lever system, whereby a predetermined rise on said cam is accurately transferred to said lever system.

4. In a screw machine, the combination of, a 15 spindle adapted to be moved axially for feeding work stock past the turning tools of the screw machine, a lever system for producing axial movement of said spindle, cam means for producing movement in said lever system, one of the 20 levers in said system having an end thereof adjacent said cam movable in an arcuate path and adapted to receive motion imparted thereto from said cam, and means carried by said lever and movable in a straight line radially from said 25 cam for transmitting the straight line motion of the cam engaging means to said end of said lever, whereby a predetermined rise on said cam is accurately transmitted to said end of said lever and thus through said lever system to said 30 spindle.

5. In a screw machine, the combination of, a 35 spindle movable axially for feeding work stock past the turning tools of the screw machine, rotatable cam means for producing movement of said spindle, a lever system interposed between said cam means and said spindle to move the spindle upon rotation of the cam means, one of the 40 levers in said system having an end thereof adjacent said cam movable in an arcuate path and adapted to receive motion imparted thereto directly from said cam, and a cam follower carried by said end of the lever and having means guiding the same in a straight line radially from said cam and including means for transmitting the straight line motion of said follower to said 45 end of said lever for accurately transmitting a predetermined cam rise to said end of said lever to move said spindle a determined amount.

6. In a screw machine, the combination of, a 50 spindle movable axially for feeding work stock past the turning tools of the screw machine, rotatable cam means for producing movement of said spindle, a lever system interposed between said cam means and said spindle to move the spindle upon rotation of the cam means, one of the 55 levers in said system having an end thereof adjacent said cam movable in an arcuate path and adapted to receive motion imparted thereto from said cam, a cam follower supported entirely from said end of the lever, means for guiding said follower in a straight line motion radially from said cam, a shoe carried by said end of said lever supporting said follower and movable at a right angle to the movement of said follower to transmit the straight line motion of said follower to said end of said lever for accurately transmitting a predetermined rise on said cam to said 60 end of said lever.

7. In a screw machine, the combination of, a 65 spindle movable axially for feeding the work stock past the turning tools of the screw machine, rotatable cam means for producing movement of said spindle, a lever system interposed between said cam means and said spindle to move the spindle upon rotation of the cam means,

one of the levers in said system having an end thereof adjacent said cam movable in an arcuate path and adapted to receive motion imparted thereto directly from said cam, a cam follower arranged to engage the periphery of said cam carried by the end of said lever and having means guiding the same in a straight line radially from said cam, and a shoe pivotally connected with the end of said lever and guided for movements in said follower transversely of the line in which said follower moves, said parts constructed and arranged for transmitting the straight line motion of said follower to said end of said lever for accurately transmitting a predetermined cam rise to said end of said lever to move said spindle a determined amount.

8. A motion transmitting system for a screw machine that has a spindle movable axially relative to work tools upon the screw machine and a cam shaft that carries cam members for producing work movement of the tools and axial movement of the spindle wherein the cam shaft extends longitudinally adjacent the spindle of the screw machine and includes in combination, a cam carried by the cam shaft of the screw machine rotatable thereby for producing axial movement of the spindle of the machine, a cam follower engaging the periphery of said cam, guide means carried by the machine for directing the motion of the cam follower in a straight line radially from said cam, a shoe movable on said cam follower for movement at a right angle relative to the movement of the cam follower, and a lever system interposed between said cam and the spindle of the screw machine operably connected to said shoe to receive and transmit mo-

tion from said cam to the spindle of the screw machine accurately for each predetermined rise on the cam.

9. A motion transmitting system for a screw machine that has a spindle movable axially relative to work tools upon the screw machine and a cam shaft that carries cam members for producing work movement of the tools and axial movement of the spindle wherein the cam shaft extends longitudinally adjacent the spindle of the screw machine and includes in combination, a cam carried by the cam shaft of the machine for causing axial movement of the spindle, a cam follower engaging the periphery of said cam for movement thereby, guide means on the machine for guiding said follower in a straight line motion radially from said cam and normal to the axis of rotation thereof, a lever pivotally mounted adjacent said cam, a shoe movable in and carried by said follower for movement normal to the line of movement of said follower and having means engaging one end of said lever to transmit motion to said end of said lever, a second lever pivotally mounted on said machine for oscillation angularly to the oscillating movement of the first lever means and having means engaging the first lever means to receive motion therefrom as imparted thereto upon a straight surface to establish a straight line movement between the two lever means, and means carried by said second lever means for operably engaging said spindle of the machine and imparting thereto movement by straight line motion between the said means and the spindle of the machine.

DELBERT I. WILSON.
